Primary Examiner—Cathron B. Matta*Attorney, Agent, or Firm*—George F. Bethel[57] CLAIM

I claim the ornamental design for a bottle insert, as shown and described.

DESCRIPTION

FIG. 1 shows a perspective view of my bottle insert.

FIG. 2 shows a side elevation view looking from the opposite side of the showing in FIG. 1.

FIG. 3 shows an end elevation view that is the same on both ends.

FIG. 4 shows a bottom plan view that is the same as the top plan view of FIG. 1; and,

FIG. 5 shows a view of the bottle insert in conjunction with a bottle.

The broken line showing of a bottle is for illustrative purposes only and forms no part of the claimed design.
